S. S. STRASBURG.

DRIER.

APPLICATION FILED AUG. 8, 1921.

1,405,460.

Patented Feb. 7, 1922.

UNITED STATES PATENT OFFICE.

SAMUEL STEPHEN STRASBURG, OF ST. MARYS, OHIO.

DRIER.

1,405,460.

Specification of Letters Patent. Patented Feb. 7, 1922.

Application filed August 8, 1921. Serial No. 490,680.

To all whom it may concern:

Be it known that I, SAMUEL STEPHEN STRASBURG, a citizen of the United States, residing at St. Marys, in the county of 5 Auglaize and State of Ohio, have invented a new and useful Drier, of which the following is a specification.

The device forming the subject matter of this application is a drier, adapted to be 10 used for handling fruit, vegetables, clothes or anything else which requires to be dried.

The invention aims to provide a structure which may be used in comparatively small size, or in comparatively large size, at the 15 will of an operator, novel means being provided for caring for the water of condensation.

It is within the province of the disclosure to improve generally and to enhance the 20 utility of devices of that type to which the invention appertains.

With the above and other objects in view, which will appear as the description proceeds, the invention resides in the combination 25 and arrangement of parts and in the details of construction hereinafter described and claimed, it being understood that, within the scope of what is claimed, changes in the precise embodiment of the invention 30 shown can be made without departing from the spirit of the invention.

In the accompanying drawings:

Figure 1 shows in longitudinal section, a device constructed in accordance with the 35 invention, parts appearing in section; Figure 2 is a cross section on the line 2—2 of Figure 1; Figure 3 is a sectional elevation showing a slight modification in the invention.

40 The device forming the subject matter of this application embodies a plurality of units, each unit including an outer member or pan 1, including a side wall 2 and a downwardly inclined bottom 3, there being an 45 opening 4 in the lowermost portion of the bottom 3. A tube 9 is provided and is secured in the opening 4 of the bottom 3, the tube 9 having inlet openings 10 disposed flush with the lowermost portion of the bottom 3. On the upper end of the tube 9, a deflector 11, in the form of a disk, is secured.

50 Each unit includes an inner member 5, in the form of a pan, comprising a side wall 6 and a bottom 7, the bottom 7 being flat, if desired. The bottom 7 is provided with an

opening 25. Each inner member 5 fits closely but slidably in one of the outer members 1, the side wall 6 of the inner member 5 being in close contact with the side wall 60 2 of the outer member 1. The side wall 6 of the inner member 5 is provided upon its upper edge with supporting elements 8, which may be hooks, the hooks engaging the upper edge of the side wall 2 of the outer 65 member 1.

The lower end of the tube 9 of one unit is received removably in the opening 25 of the bottom 7 of the inner member 5 of the next unit below, it being possible to dispose 70 as many units as desired, one above the other, as depicted in Figure 1, and it being possible not only to separate one unit from another unit, but, as well, to separate the constituent members 1 and 5 of each unit. 75 The lower end of an escape pipe 12 is received removably in the opening 25 of the uppermost inner member 5.

Any suitable means may be provided for heating and supporting the structure 80 above described. Thus, if desired, a support 14 may be supplied, the same including standards 15 connected at their upper ends, for reinforcement, by an upper frame 16, and connected intermediate 85 their ends by a lower frame 17. The bottom 3 of the outer member 1 of the lowermost units rests on the lower frame 17, all of the superposed units thus being supported as shown in Figure 1. It may be expedient to place a small boiler 18 below the lowermost unit, the boiler being mounted in any suitable way, as shown at 19 on the standards 15 of the support 14. The boiler 18 has a nipple 20 into which the lowermost 90 tube 9 extends, the boiler being equipped with a filling tube 21 carrying a removable cap 22. The boiler 18 and its contents may be heated by a burner 23 of any preferred sort.

100 Assuming that a boiler 18 is used, the steam from the boiler ascends through the lowermost tube 9, and, being deflected by the member 11 comes into contact with the inner member 5 of the lowermost unit, the member 5 being heated and its contents being dried. The steam ascends, then, through the other tubes 9 and should there be any exhaust, the exhaust is conducted away by the pipe 12. The water of condensation is received on the 110 bottom 3, and, following the inclination of the bottom, enters the tube 9 through the

inlets 10, the water thus being returned to the boiler 18. The boiler 18 preferably operates at atmospheric pressure only, and since there is a considerable amount of condensation, it is not necessary to fill the boiler with water frequently. The contacts between the parts 6 and 2 is sufficiently close to prevent the escape of steam at the low pressure at which the device operates.

10 In order to take down the structure, it is necessary merely to withdraw the escape pipe 12 from the corresponding opening 25, to lift out the uppermost inner member 5, and to lift out the uppermost outer member 1, the tube 9 thereof being withdrawn from the opening 25 of the inner member 5 next therebelow, this operation being continued until all of the units have been removed.

In Figure 3 of the drawings, parts hereinbefore described have been designated by numerals previously used, with the suffix "a". The tube 9^a, corresponding to the tube 9 may extend downwardly into a receptacle 46, the boiler 18^a being located in any desired place at one side of the part 9^a. The conduit 47 leads from the boiler 18^a to the tube 9^a. The steam proceeding from the boiler 18^a traverses the connection 47 and the tube 9^a and ascends. The water of condensation travels downwardly through the tube 9^a and is received in the receptacle 46. The water 48 in the receptacle 46 closes the lower end of the tube 9^a and constrains the steam to move upwardly rather than downwardly, it being recalled that the boiler 18^a operates at a very low pressure. In the form shown in Figure 3 of the drawings, the water 48 is saved and may be used for any purpose, under conditions which call for a supply of pure distilled water.

What is claimed is:—

1. In a device of the class described, a

unit made up of an outer member and an inner member fitting therewithin, said members having spaced bottoms, the bottom of the inner member having an opening; a tube fixed in the bottom of the outer member and adapted to be received in the opening of the bottom of the inner member of a like unit, the tube having an aperture located close to the bottom of the outer member and forming an inlet for steam and an outlet for water of condensation. 45

2. In a device of the class described, a unit made up of an outer member and an inner member fitting therewithin, said member having spaced bottoms, the bottom of the inner member having an opening; a tube fixed in the bottom of the outer member and adapted to be received in the opening in the bottom of the inner member of a like unit, the tube having an aperture constituting an inlet for steam and an outlet for water of condensation; and a deflector mounted on 60 the upper end of the tube. 65

3. A device of the class described comprising superposed units, each unit embodying an outer member and an inner member fitting therewithin, said members having 70 spaced bottoms; a tube mounted in the bottom of one outer member and passing through the bottom of the inner member next therebelow, the tube being provided with an opening communicating with the 75 space between the bottoms of the members of the unit; and a deflector carried by the upper end of the tube.

In testimony that I claim the foregoing as my own, I have hereto affixed my signature 80 in the presence of two witnesses.

SAMUEL STEPHEN STRASBURG.
